UNITED STATES PATENT OFFICE

2,262,310

EARTH MOVER

Mack Wooldridge, San Jose, Calif., assignor, by
mesne assignments, to Wooldridge Manufacturing
Company, a corporation of Nevada

Application May 28, 1938, Serial No. 210,671

6 Claims. (Cl. 37—124)

My invention relates to transporting devices for excavating, carrying and discharging material such as earth, and is particularly concerned with a vehicle which is drawn by a tractor or other suitable motive power and during its advancement over the terrain is capable of dislodging earth from the surface thereof, of holding a very large amount of such dislodged earth, of carrying it for a protracted period, and of discharging it at a selected site, either in a single pile or spread out in a layer of a predetermined and variable thickness.

It is an object of my invention in general to improve earth movers.

Another object of the invention is to provide a novel structure incorporating a bowl having a load discharge member movable between rigid side walls, in conjunction with a forward forked frame, and which makes possible raising and lowering of the cutting blade without applying undue stresses to the bowl or frame.

Another object of the invention is to provide a machine capable of effective digging by the cutting blade, accompanied by an effective loading action.

Another object of my invention is to provide an earth mover in which the loading and unloading of the vehicle are satisfactory whether the material is sticky clay or whether it is free-flowing sand or other materials of similar, widely varying characteristics.

The foregoing and other objects are attained in the embodiment of the invention illustrated in the drawings, in which

Fig. 1 is a side elevation of an earth mover constructed in accordance with my invention, a portion of the front structure being shown in cross-section;

Fig. 2 is a plan of my earth mover;

Fig. 3 is a cross-section, the plane of which is indicated by the line 3—3 of Fig. 2, parts of the structure being shown in several positions;

Fig. 4 is a rear elevation of my earth mover;

Fig. 5 is a cross-section, the planes of which are indicated by the line 5—5 of Fig. 3;

Fig. 6 is a detailed cross-section, the plane of which is indicated by the line 6—6 of Fig. 5;

Fig. 7 is an enlarged detail in section corresponding to Fig. 3, showing especially in side elevation a mounting of the central rear wheels in one position;

Fig. 8 is a view similar to Fig. 7, showing the wheels in another position.

My earth mover incorporates a main bowl structure A having rigid side walls and a forward

cutting or digging blade, together with a member movable between the side walls between discharge and load supporting positions. In conjunction with the main bowl structure, there is a front apron or auxiliary load carrying bowl B which is movable between closed or raised positions with respect to the cutting blade. The main bowl structure is connected to a forward forked frame C.

In the form of earth mover disclosed in the drawings, the machine is adapted to be propelled over the ground by any suitable draft implement, such as a tractor (not shown). The earth mover is connected to the tractor by a drawbar 6 secured to a front truck axle 7 at the extremities of which suitable front ground-engaging members or wheels 8 are journaled. A ball 9 projecting upwardly from the axle 7 is received in a socket 11 at one extremity 12 of the frame C, whereby this frame is supported upon the ground-engaging members 8 for virtually universal movement. The draft frame C is fabricated of suitable structural shapes welded together, and includes not only an upright horn 13 but a generally horizontal, transversely spreading and elevated platform 14 diverging to provide a pair of side members 16 and 17 which extend rearwardly and downwardly to terminate in journals 18 and 19, respectively.

Situated one adjacent each of the side members are side plates 21 and 22 (forming part of the main bowl structure A) of generally planar extent and irregular outline, reinforced by suitable structural shapes welded thereto. The side plates are spanned by suitably reinforced rear end plates 23 to which, at suitable intervals, extensions or outriggers 24 are attached. The outriggers form pillow blocks for removable axles 26 and 27 of suitable ground-engaging wheels 28 and 29, respectively, which support the rear of the side plates 21 and 22.

In addition to the ground-engaging members 28 and 29, I can provide an intermediate pair of dual wheels 31 which are mounted for rising and falling movement independently of the pairs 28 and 29, so that, despite the unevenness of the terrain over which the vehicle is advancing, at least two pairs of wheels are bearing substantially equal portions of the load.

Extending from brackets 32 on the rear wall 23 are mounting cranks 33 which, adjacent the bracket 32, are journaled on pins 34 and at their other ends are joined by structural members 36 for unitary movement. Adjacent the elbow of the crank arms an axle 37 extends between them

and carries the pair of wheels 31 for movement in an arc about the axis of the pins 34. The member 35 is provided with a pair of upstanding rollers 38 which bear on the side plates 39 of a rocker frame 41 secured to the rear wall 23 by pivot pins 42. A pierced spring cup 43 is mounted by trunnions 44 in the side plates 39 and receives a coil spring 46 encompassing a stay rod 47. The lower end of this rod is secured by a pin 48 to a bracket 49 extending between the side plates 21 and 22 and is threaded at its opposite end to receive nuts 51 adjustably positioning an abutment plate 52 resting against the spring 46.

The arrangement is such, as especially shown in Figs. 7 and 8, that a variable spring resistance is offered to the rising movement of the wheels 31, so that by suitably adjusting the nuts 51 a selected proportion of the weight of the vehicle can be imposed upon such wheels. Despite undulations in the ground, therefore, the wheels 31 rise and fall independently of the wheels 28 and 29 yet bear their predetermined proportion of the load. Excessive travel of the intermediate wheels 31 is, however, prevented by stops 53 and 54 depending from the plates 39 in the path of the rollers 38.

The draft frame C and the side plates 21 and 22 of the main bowl structure A, when considered together, form a jack-knife assembly, the parts of which pivot respectively about the axis of the ground-engaging front wheels and the ground-engaging rear wheels. In order to establish the relative position of the members of the jack-knife assembly, or in order to move the side plates 21 and 22 about the axis of the rear wheels, I provide an equalized actuating device. A cable 61, extending from a power-operated winch driven by the tractor and controlled by the operator thereof, extends through a fair lead 62 mounted on the horn 13 and over a pulley 63 to 40 a differential drum 64 rotatably mounted on a vertical shaft 66 projecting upwardly from the platform 14 and aligned by suitable bracing 67. The cable 61 has one end fast on and is wrapped several times around a large sheave 68 included in the differential drum 64. Also included in the drum is a small sheave 69, to which a secondary cable 65 is fastened and around which the cable 65 is several times wrapped. With the differential drum arrangement, when the cable 61 is taken in, for example, the sheave 68 is rotated in unison with the sheave 69 and a relatively small tension in the cable 61 becomes a correspondingly larger tension in the cable 65.

From the sheave 69 the cable 65 extends around a pulley 71, thence around a comparable pulley 72, and is anchored by a bolt 73 upon the bracing 67. When the cable 63 is taken in, therefore, the pulleys 71 and 72 are caused to approach each other with an equalized force. Movement of the pulleys 71 and 72 is transmitted to the side plates 21 and 22 by identical mechanisms. Each pulley is connected by a short cable 74 trained around a horizontal sheave 76 and a vertical sheave 77 mounted upon the members 16 and 17 to a pin connection 78 at the forward part of each of the side plates 21 and 22.

The effect of the arrangement is that when the cable 61 is taken in by its winch, the differential drum 64 is rotated counterclockwise, as seen in Fig. 2, the pulleys 71 and 72 approach each other, and the side plates 21 and 22 rise with respect to the ground and rotate clockwise, as seen in Fig. 1, about the ground-engaging wheel axles 26 and 27. Comparably, when the cable

61 is paid out by its winch, the weight of the side plates 21 and 22 and their associated parts is sufficient to draw the pulleys 71 and 72 apart, and to rotate the differential drum 64 in a clockwise direction, as seen in Fig. 2, in response to the paying out of the cable 61.

The raising and lowering movement described above is effective to control the elevation of the cutting or digging blade 81. This blade extends horizontally and transversely between the forward ends of the side plates and is rigidly secured thereto. The blade 81 itself can be sharpened or preferably includes a detachable cutting edge 82 of special material which can be replaced or resharpened from time to time. The relative position of the cutting edge 82 determines the depth of cut when material is being excavated and determines the elevation of material being spread.

To enable discharge of material from the main bowl structure A, I provide a member movable between the sides of the bowl between loading and discharge positions. This member is shown as a bottom or pan 83 which is disposed between the side plates 21 and 22, and which extends rearwardly from the blade 81. It is secured either to the blade or adjacent the blade by hinge 84 for movement about a transverse horizontal axis. This hinge can be a rod which extends through alternate serrated portions 87 and 88 on the blade 81 and the pan 83, respectively. The pan 83 is preferably fabricated of a plurality of sheets of material and structural shapes to provide a relatively light though rigid construction. Reinforcing struts 81 are shown extending from enlargements of relatively low sides 92 included in the pan. In its lowermost or earth-carrying position illustrated in Figure 3, the weight of the pan and its load is borne not only by the hinge 84 but likewise by a stop formed by an angle 93 spanning the side plates 21 and 22.

In order to normally urge the pan toward its earth-carrying position, I preferably provide a yielding means, such as a spring, normally effective to urge the pan into abutment with the cross-member 93. To accomplish this, I attach a cable 94 to a convenient portion of the pan and train the cable around a pulley 96 secured to the cross-member 93 and around a pulley 97 mounted on a transverse box frame 98 spanning the space between the side plates 21 and 22 and serving as a continuation also of the back plate 23. From the pulley 97 the cable passes around a pair of pulleys 100 and 99 mounted within the box frame and is secured to a terminus 101 thereupon.

Each of the pulleys 100 and 99 is secured to one of similar plungers 102 disposed within one of a pair of coil springs 103 surrounding comparable guides 104 at the ends of the box beam and removably mounted therein by stud-secured plates 106. When the pan 83 is rotated about the hinge axis 84 to tension the cable 94, the pulleys 100 and 99 are moved first to approach each other as seen in Fig. 5, or in a direction to compress their respective springs, the pulleys being constrained to substantially rectilinear movement by guide walls 107 within the box beam. When the superior force is released from the pan 83 the springs 103 are effective, through the agency of the cable 94, to return the pan 83 to its seat against the angle 93 and to hold it firmly thereagainst with a predetermined force.

In conjunction with the main bowl structure A, I provide a movable front apron or auxiliary load carrying bowl B. The front apron includes a load supporting wall formed by plates 111 and

112, which are attached to the side plates 113 and the front plate 114. Attached to the side plates 113 are the mounting arms 116. These arms are connected by transversely aligned pivots 117 to the side walls 21 and 22, so that the apron moves about the pivots 117 as a center or axis.

In order to avoid any overlapping of the side plates, and yet to preclude the accidental spill of excavated material between the apron B and the side plates, I arrange the contour of the side plates 21 and 22 so that their boundary is arcuate, as at 118, about the pivot pins 117 as a center. Thus, as the apron rotates about the pins 117, the clearance between the plate 113 and the plates 21 and 22 remains substantially constant.

In its lowermost or closed position, the apron B rests against the cutting edge 82, and I preferably provide means for lifting the hood from such lowermost or closed position into an upper or raised position. Furthermore, I preferably correlate such raising or lifting means with a means for exerting a lifting force upon the pan 83. Extending from a power-operated winch on the tractor, which is controlled by the tractor operator, is an operating cable 121. The cable 121 passes through a fair lead 122 mounted on the horn 13 and through a pulley 124 supported by the framework 67 and is convoluted around and fastened to the larger sheave 126 of a differential drum mechanism which includes a shaft 127 journaled on an A-frame 128 upstanding from the side walls 21 and 22. This differential drum mechanism can be termed a motion transmission unit which affords a mechanical advantage in transmitting forces.

At each end of the shaft 127 there is a relatively small drum 129 to which and around which a cable 131 is secured. Each of the cables 131 extends first to pass around a pulley 132 mounted on a cross-pin 133 at the upper and rearmost extremity of the pan 83. The cable 131 then extends forwardly over a vertical sheave 134 at one side of the A-frame 128, then extends over a pulley 136 mounted on a cross-pin 137 adjacent one corner of the front plate 114 of the apron B. From the pulley 136 the cable extends upwardly to an anchorage 138 on the A-frame 128.

When the cable 121 is tensioned, it rotates the sheave 126 in a counterclockwise direction, as seen in Fig. 1. This simultaneously rotates the shaft 127 and the drums 129. The cables 131 are then tensioned and urge the pulleys 132 and 136 to approach each other. Due to the retarding effect of the springs 103, and due to the greater load ordinarily carried on the pan 83, ordinarily the apron B is first to yield and is rotated about the pivots 117 until it arrives at an uppermost position as indicated by the dotted line in Fig. 3. In its uppermost position the apron abuts against the A-frame 128 so that continued tension on the cables 131 results in moving the pulleys 132 upwardly and forwardly and rotates the pan 83 about the hinge 84 until it likewise assumes the dotted line discharge position shown in Fig. 3.

During the pivotal movement of the pan it is effective to dislodge any material which might be of a clayey or adhesive nature and adhere to the sides 21 and 22, so that there has been a virtually total discharge of the contents of the apron and of the bowl A when the apron and the pan have both reached their fully raised positions. After such discharge, the cable 121 is permitted to slacken, and the springs 103, together with the weight of the pan and of the apron, are effective

to return such elements to their load carrying or lowermost position.

The machine described above is employed as follows: To take on a load, the machine is traversed over a ground surface and the operator raises the front apron B by pulling on cable 121, and lowers the main bowl structure A and the cutting blade by playing out cable 61, until a cut is being taken at the desired depth. The dirt is delivered into the main bowl structure A upon the pan or hinged bottom 83. As the load nears capacity, a part of the load is carried by the front apron B, and as the cut is being completed and the blade is being raised by pulling on cable 61, cable 121 can be played out to permit closing of the front apron. Continued pulling on cable 61 serves to raise the main bowl structure A free of the ground so that the machine can be traversed to the location where the load is to be discharged. When it is desired to discharge the load, the operator pulls upon cable 121, which causes raising of the front apron B, thus causing discharge of the forward part of the load. Continued pulling or takeup of cable 121 ultimately causes the pan or hinged bottom 83 to be swung upwardly and forwardly to its raised or discharge position, thus causing the remainder of the load to be discharged.

My machine has several desirable features. The combination between the forked frame C and the main bowl structure A makes a strong and durable assembly, and the arrangement for raising and lowering the main bowl structure in conjunction with this assembly makes for good control over the depth of cut without applying undue stresses to various parts of the machine. The pivotal connections 18 to the sides of the main bowl are located in a desirable manner, rearwardly of the cutting blade and forwardly of the rear wheels, so that the draft is effectively applied through the rigid side walls of the bowl to the cutting blade, without tendency to have such forces urge the blade out of the ground. The angle of the blade is such that in normal cutting the blade and also the main bowl are urged downwardly against the pull of cables 74.

I claim:

1. In earth moving equipment, a frame, wheels serving to carry the forward end of the frame, a main bowl structure associated with the frame and provided with a forward digging blade, wheels serving to support the rear end of the bowl structure, means forming a pivotal connection between the bowl and the frame on a transverse axis spaced rearwardly of the blade, and means acting between the frame and the forward portion of the bowl for raising and lowering the bowl, said means including cables attached to the sides of the bowl, an operating cable, and means for transmitting approximately equalized tension from said operating cable to said first named cables.

2. In earth moving equipment, a frame, wheels serving to carry the forward end of the frame, a main bowl associated with the frame and provided with a forward digging blade, wheels serving to support the rear end of the bowl, means forming a pivotal connection between the bowl and the frame on a transverse axis spaced rearwardly of the blade, and means acting between the frame and the forward portion of the bowl for raising and lowering the bowl, said means including cables attached to the sides of the bowl adjacent the forward end of the bowl, an operating cable, and means including sheave blocks for

transmitting approximately equalized tension from said operating cable to said first named cables.

3. In earth moving equipment, a frame, wheels serving to carry the forward end of the frame, a main bowl associated with the frame and provided with a forward digging blade, wheels serving to support the rear end of the bowl, means forming a pivotal connection between the bowl and the frame on a transverse axis spaced rearwardly of the blade, and means acting between the frame and the forward portion of the bowl for raising and lowering the bowl, said means including cables attached to the sides of the bowl at the forward end of the bowl, sheaves carried by the sides of the frame and over which said cables engage, an operating cable, and means including a pair of sheave blocks serving to transmit approximately equalized tension from said operating cable to both said first named cables.

4. In earth moving equipment, a forked frame, wheels connected to the forward end of the frame for supporting the same, a bowl structure mounted in the forked end of the frame and including reinforced side walls, a transverse earth cutting blade secured to the forward end of the bowl structure, rear supporting wheels, rear extensions secured to said bowl structure and serving to connect the bowl structure to said wheels, a pivotal connection between the rear ends of the frame and the side walls of the bowl, and means acting between the frame and the forward end of the bowl structure for raising and

lowering the bowl structure, the axis of said pivotal connection being located above a plane containing said cutting blade and the axis of said rear supporting wheels, and also being located relatively close to the axis of the rear wheels compared to its distance from the cutting blade.

5. In earth moving equipment, a forked frame, wheels serving to carry the forward end of the frame, a main bowl structure associated with the frame and provided with a forward digging blade and rigid side walls, wheels serving to support the rear end of the bowl structure, means forming a pivotal connection between the rear end of the forked frame and the side walls of the bowl on a transverse axis spaced rearwardly of the blade, and means acting between the frame and the forward portion of the bowl for raising and lowering the bowl, said means including cables connected to the sides of the bowl, an operating cable, and means for applying approximately equalized tension from the operating cable to said first named cables.

6. In earth moving equipment having a frame and a bowl structure adjustable carried thereby, a pair of cables attached to said bowl structure at spaced points, spaced apart sheave means on said frame about which the respective cables are reeved, and operating means for said cables including a pair of movable sheave blocks and an operating cable reeved over the sheaves of said blocks, said first named cables being attached respectively to said blocks.

MACK WOOLDRIDGE
